UNITED STATES PATENT OFFICE.

GEORGE A. L'HOMMEDIEU, OF ATLANTIC CITY, NEW JERSEY.

BATH-TUB ATTACHMENT.

1,104,430.

Specification of Letters Patent. Patented July 21, 1912.

Application filed March 21, 1914. Serial No. 826,824.

To all whom it may concern:

Be it known that I, GEORGE A. L'HOMMEDIEU, a citizen of the United States, residing at Atlantic City, in the county of Atlantic and State of New Jersey, have invented certain new and useful Improvements in Bath-Tub Attachments, of which the following is a specification, reference being had to the accompanying drawings.

10 This invention relates to bath tubs.

The object of the invention is, in a ready, practical and inexpensive manner, and without adding materially to its cost of production, or in any way detracting from its appearance, to adapt a bath tub for suspending various bath room accessories, such as towels, a bath rug, a brush, a dust pan, a hot water bottle and the like, in positions where they will be readily accessible when needed for use, and yet be out of the way, thus to avoid contact between such articles and a person cleaning around or under the tub.

With the above and other objects in view, as will appear as the nature of the invention is better understood, the same consists, generally stated, in combining with the underside of the roll rim of the bath tub, a plurality of brackets which are preferably cast integral with the rim and are designed to support a rod or rods from which may be suspended the various accessories usually found in a well equipped bath room. The brackets at the sides of the tub will be of ring form, while those at the ends will be of hook form, the object of this arrangement being in the first place to permit the assemblage with the side brackets of straight rods, and in the second place to permit assemblage with the end brackets of curved rods conforming in contour to that of the ends of the tub. These rods, in themselves, may constitute a suspending means for various articles, such as towels, wash rags, bath rugs and the like, but as a matter of further and specific improvement, it is preferred to combine with the rods at the sides of the tub, swinging racks for supporting textile articles, while the rods at the ends of the tub may have combined with them hooks from which may be suspended brushes, a dust pan, a water bag or the like. Generally, it will be preferred to furnish the bath tub equipped with the rods and hangers and hooks, but it is to be understood that the invention is not to be limited

thereto, as the tub may be sold with the brackets combined with the rim, and the various dealers furnish the tub with such suspending means as may be in demand. 60 Substantially the same idea can be carried out in connection with a stationary wash basin having a roll rim, as will hereinafter appear.

Further and more specific details of construction will be hereinafter described and claimed.

In the accompanying drawings forming a part of this specification, and in which like characters of reference indicate corresponding parts: Figure 1 is a view in vertical longitudinal section through a bath tub equipped with the improvements of the present invention. Fig. 2 is a top plan view thereof. Fig. 3 is an enlarged detail view of one portion of the attachment. Fig. 4 is a similar view of another portion thereof. Fig. 5 is a view in side elevation, partly in section, displaying the manner in which a towel rack is combined with the bath tub 80 attachment. Fig. 6 is a vertical longitudinal sectional view showing the idea applied to a stationary wash basin. Fig. 7 is a horizontal sectional view taken on the line 7—7 of Fig. 6.

Referring to the drawings, B designates an ordinary enamel bath tub and R the roll rim thereof. Cast integral with the tub and the rim is a series of brackets which are arranged at the sides and ends of the tub, 90 and of which any desired number may be employed, in the present instance four of the brackets being shown at each side of the tub and one at each end thereof. The brackets 1 at the sides of the tub are arranged in juxtaposed pairs and are of ring form, that is to say are provided with a circular orifice 2, while those at the end of the tub are each provided with a hook 3. It is desired that these brackets shall be so disposed relative to the rim as not to detract from the appearance of the tub, so that the inclusion of such an improvement can be no cause of objection to a purchaser.

Engaging the two intermediate brackets 105 at each side of the tub is a rod or bar 4, which will preferably be tubular, and has its terminals threaded to be engaged by nuts 5 by which the bar is held in position. Loosely mounted upon each of these bars, or 110 on one as may be preferred, is a pair of hangers 6, the upper ends of which are pro-

vided with eyes 7 to engage the bars, and the lower ends with similar eyes 8 to engage a rod 9 herein shown as provided at its ends with knobs 10 to prevent accidental removal, the rod 9 serving as a means for suspending towels, a bath robe, or the like.

The two exterior or outside brackets 1 are engaged, at each end of the tub, by bars 11 and 12, respectively, the bar 11 being disposed at the foot of the tub and engaged with the hooked bracket 3, and having its ends passed through the two adjacent exterior brackets 1, and held in position by nuts screwed on its ends, the rod 12 being curved to conform to the head of the tub and being similarly combined with the two exterior brackets 1.

To adapt the structure for supporting small articles such as brushes, a dust pan or the like, hooks 13 are furnished, the upper end of the shank of each of which is provided with an eye 14, one or more of these hooks being disposed at the head or foot of the tub, and being suspended by the eye respectively from the rods 11 and 12.

In carrying the invention into effect in connection with a stationary wash basin having a roll rim, such as are now commonly employed, the front wall 15 of the rim, as shown in Fig. 6 will be provided with a hook bracket 16, and the rear wall 17 with two eye brackets 18, and disposed within the roll and engaging at its bend with the hook 16 is a U-shaped rod 19, the terminals of which are threaded and project through the openings in the brackets 18. The threaded terminals are engaged by nuts

20 which, by being turned up tightly against the lugs will exert a tension upon the rod and cause its bend firmly to engage with the bracket 16, and thus hold the rod in place against accidental disconnection from the basin.

From the foregoing description it will be seen that while the improvements herein defined are simple in character, they will be thoroughly efficient in the production of a novel and desirable attachment for a bath tub, and further that the adoption of such means will not materially add to the cost of manufacture of the tub.

I claim:

1. The combination with the roll rim of a bath tub, of brackets disposed within the rim, those at the sides of the tub being of ring form and those at the ends of hook form.

2. The combination with the roll rim of a bath tub, of brackets disposed within the rim, and sectional rods engaging the brackets.

3. A lavatorial appliance provided with a roll rim and with hook and eye brackets disposed within the rim, a rod arranged to engage the brackets, and nuts carried by the terminals of the rods to secure the latter in position.

In testimony whereof I hereunto affix my signature in the presence of two witnesses.

GEORGE A. L'HOMMEDIEU.
